UNITED STATES PATENT OFFICE.

JOHN GRAHAM, OF CHICAGO, ILLINOIS.

DESIGN FOR A COMBINATION TYPE ORNAMENT.

SPECIFICATION forming part of Design No. 16,522, dated February 16, 1886.

Application filed November 13, 1885. Serial No. 182,702. Term of patent 3½ years.

To all whom it may concern:

Be it known that I, JOHN GRAHAM, a citizen of the United States of America, residing at Chicago, in the county of Cook and State of Illinois, have invented and produced a new and original Design for Combination Type Ornament for Letter-Press Printing, of which the following is a specification, reference being had therein to the accompanying illustration.

My invention consists of a new design for combination type ornaments for letter-press printing, as shown in the accompanying illustrations, and as hereinafter described and claimed.

For convenience of reference to the different parts of the ornaments, they are numbered as shown in the illustrations.

No. 1 is a corner-piece having the lines of the lower forward corner partly turned over and having dotted lines under the turned-over corner. The forward portion of this ornament is formed to join and combine readily with Nos. 2, 3, and 4. The lower and forward portions of 1 and all the parts of 2, 3, and 4 consist of broken lines formed by short dark separated lines, as shown, and each of these pieces 2, 3, and 4 are shaped to join and combine readily with any side of each other. The central portion of 5 is diamond shape, having its upper left and lower right angles extended to the corners of the ornament and dark lines extended from the other angles of the center piece to the other corners of the ornament. The central portion of 6 is quadrangular, having its lower right angle extended into the corner of the ornament and dark lines extended from the sides of the center piece to the other corners of the ornament. The central portion of 7 is circular, connecting with dark lines extended to the corners of the ornament.

No. 8 is a square, and 9 is a half-square, to

be combined in any required number in forming large squares used for tints in colored printing.

45

No. 10 is a square ornament having a quadrangular central portion and dark lines extended to the four sides and angles of the ornament. Any number of this ornament may be combined with itself to form any required 50 number of different designs.

Nos. 11 and 12 are narrow dotted pieces, to be combined with the other ornaments as required.

13 is a dotted piece having a central top 55 point.

14 is a dotted piece having two points on the top and one point on the forward end.

Nos. 15 to 21, inclusive, all have top and bottom dark lines and one or more vertical or 60 inclined dark lines extended from the top to the bottom lines, and are designed to represent, when properly combined, the skin of an alligator.

No. 15 has circular designs on each side of 65 the central line.

What I claim as new, and desire to secure by Letters Patent, is—

The design for combination type ornaments for letter-press printing, consisting of the separate portions of the ornaments, formed entirely of broken lines having angular and circular central portions, and dark lines having dark lines and light-shaded portions, and corner-pieces partly of broken and partly of unbroken straight and angular lines, all adapted to be combined together as described and shown.

In testimony whereof I affix my signature in presence of two witnesses.

JOHN GRAHAM.
